(57) **CLAIM**

We claim the ornamental design for an instrument having oblique mounted terminal posts, substantially as shown and described.

DESCRIPTION

FIG. 1 is an isometric view of a first embodiment of an instrument having oblique mounted terminal posts showing our new design;

FIG. 2 is an isometric view of a second embodiment of an instrument having oblique mounted terminal posts showing our new design;

FIG. 3 is an isometric view of a third embodiment of an instrument having oblique mounted terminal posts showing our new design; and,

FIG. 4 is an isometric view of a fourth embodiment of an instrument having oblique mounted terminal posts showing our new design.

The broken line portion of the figure drawings is included to show unclaimed subject matter only and forms no part of the claimed design.
